ICE SKATE SCABBARD

Richard N. Kesner, Needham, and Herbert B. Hawes,
East Brookfield, Mass., assignors to St. Lawrence
Manufacturing Company, Inc., Giffard, Quebec, Can-
ada, a corporation of Quebec

Filed Apr. 5, 1960, Ser. No. 60,656

Term of patent 14 years

(Cl. D34—5)

Fig. 1

Fig. 2

Fig. 3

Fig. 4

Fig. 5

Fig. 1 is a perspective view of the ice skate scabbard, illustrating the position of the members in skate holding relation.

Fig. 2 is a side elevational view thereof.

Figs. 3 and 4 are respectively a top plan view and bottom view of the scabbard members shown in Figs. 1 and 2 with the coil portion shown fragmentarily for convenience of illustration.

Fig. 5 is a side view of the scabbard, in collapsed position.

We claim:

The ornamental design for ice skate scabbard, as shown and described.
